UNITED STATES PATENT OFFICE.

FRANK L. DODGSON, OF ROCHESTER, NEW YORK, ASSIGNOR TO GENERAL RAILWAY SIGNAL COMPANY, OF ROCHESTER, N. Y.

TRAIN CONTROL.

Application filed November 20, 1924. Serial No. 751,120.

This invention relates to automatic train control systems for railroads and more particularly to such systems of the continuous inductive control type employing a 3-position 5 relay on the train controllable to give any one of three different indications.

One of the principal objects of the present invention is to provide absolute stop control for enforcing obedience to "stop-and-stay" 10 interlock signals, in addition to speed control for enforcing obedience to the indications of automatic block signals. In accordance with this invention, it is proposed to provide an automatic brake application which occurs irrespective of the speed of the train and which 15 can not be prevented by the engineer, whenever there is a change directly from clear or proceed to stop or danger, without an intervening change to caution. It is also proposed 20 to provide such absolute stop control in addition to the provisions for acknowledgment of caution and permissive stop signals.

Various specific objects, advantages and 25 characteristic features of the invention will be in part obvious and in part pointed out as the description progresses.

In the accompanying drawings, Fig. 1 shows in a simplified and diagrammatic manner the trackway equipment of this invention 30 for automatic block signal territory, together with the impulse receiving devices and a control relay for the locomotive or other vehicle, speed-distance curves of permissive speed limits, and interrupted lines for indicating 35 the points during the travel of the train at which certain contacts open and close;

Fig. 2 illustrates diagrammatically in perspective a simplified arrangement of operating gearing and associated parts, constituting 40 a portion of the car-carried apparatus, this gearing and its control devices providing for the operation of speed-distance contacts, and distance contacts;

Fig. 3 illustrates diagrammatically and in 45 accordance with some recognized and some arbitrary conventions the various parts and devices of the car-carried apparatus and their circuit connections; and

Fig. 4 illustrates how the trackway equipment 50 for automatic block signal territory, as shown in Fig. 1, is modified and organized to provide for reduced speed control and absolute stop upon the approach to a stop-and-stay interlock signal.

A specific organization of devices and cir-

cuits, selected to exemplify one embodiment of the invention and herein shown and described, includes in some particulars structures and combinations, disclosed and claimed in prior applications filed by myself and others. For example, the specific system herein shown and described, is similar to that disclosed in the Howe application, Ser. No. 746,578, filed October 29, 1924, the present invention being in effect, generally stated a 60 modification or adaptation of this type of system to incorporate therein the provision of a modified form of an absolute stop control.

Trackway equipment.—The trackway devices and control circuits for automatic block signal territory are the same as those of a continuous inductive control system of the type using a 3-position car relay, with track phase and line phase circuits. Alternating current 70 track circuits are illustrated in the particular form shown, but it should be understood that the invention is applicable to direct current 75 track circuits by employing the well known expedients, such as shown in the Howe application mentioned above, for applying track phase and line phase train control currents to direct current track circuits.

Referring to Fig. 1 there is shown a typical railway signaling system in which the track 80 rails 1 are divided by insulating joints 2 into blocks, of which the block I and the adjacent ends of two other blocks H and J only have been shown. Since the various blocks are the same like parts of each block 85 are designated by like reference characters having distinctive exponents. For simplicity it is assumed that the length of these blocks corresponds to braking distance and includes only one track circuit, various 90 expedients (not shown) being employed to adapt the system to blocks of various lengths and those including cut sections. At the entrance end of the block I, the normal direction of traffic being as indicated by the arrow, 95 is a track relay 3 of the alternating current type, this track relay being energized by current impressed across the exit end of the block I by a track transformer 4 having its primary winding connected to the secondary 100 winding of a transformer 5 which receives its energy from a transmission line 6. Although 105 train control systems of the three-position inductive type such as the present system, may be used in connection with trackway 110

apparatus in which no wayside signals are used, signals of either the color light or semaphore type may be used, and for convenience semaphore signals Z of the three-position type have been shown without attempting to illustrate their well known operating mechanism and control circuits.

The apparatus thus far described is that which is necessary for wayside signal control purposes. In addition to this apparatus means are provided for conducting an alternating current flowing in the same direction in the two track rails in multiple and having a predetermined phase relation with the track circuit current supplied by the transformer 4.

In the particular arrangement shown this simplex or line current is caused to flow through a circuit including the two rails in multiple by applying alternating current potential to the two mid points of balancing resistances bridged across the entrance end and exit end of the block respectively, which circuit may have its polarity reversed if the block in advance becomes occupied. This simplex or line circuit may be traced as follows:—Beginning at the secondary winding of the transformer 7¹, wires 8¹ and 9¹, front contact 10¹ of the track relay 3¹, wire 11, to the mid-point of balancing resistance 12 through the two rails in multiple to the entrance end of the block I to the mid-point of balancing resistance 13, wire 14, front contact 15¹ of the track relay 3¹, wire 16¹ back to the secondary winding of the transformer 7¹. When the track relay 3¹ is de-energized current is reversed in this circuit as is obvious by looking at the pole changer contacts 10¹ and 15¹.

Referring now to Fig. 4, which illustrates a continuation of the trackway apparatus shown in Fig. 1, there has been shown the block K and the adjacent ends of the blocks J and L of which the block L is located in interlocking territory. Since many of the parts of the trackway apparatus shown in Fig. 4 are the same as those shown in Fig. 1, such parts are designated by like reference characters having distinctive exponents. It should be noted that the signals Z^2 and ZA are distant and home signals respectively to the interlocking territory shown and for this reason these signals have been illustrated with square blades. The dotted rectangle shown illustrates an interlocking tower which among other things includes a lever 27 which under normal stop condition, as shown, maintains the signals Z^2 and ZA at the caution and stop position respectively in the absence of a train in the block K, but if the block K is occupied the signal Z^2 will, of course, also indicate danger.

This lever 27 is suitably interlocked with levers of conflicting routes, such as, crossings, sidings, etc. so that the signal ZA which is an absolute stop-and-stay signal must as-

sume the danger position before the switch for such siding may be opened or the derail for such crossing may be closed. It may be mentioned at this time that the practice heretofore has been to provide a derail just beyond a stop-and-stay signal, such as the signal ZA , which was opened when the signal was at stop so as to assure that a train would not pass such stop-and-stay signal when at danger. In accordance with the present invention it is proposed to effect an automatic brake application regardless of speed instead of a derailment when a train passes such a stop-and-stay signal ZA . In addition to the balancing resistances 12² and 13² heretofore mentioned there are provided balancing resistances 28 and 29 in the block K, so that, a plurality of simplex circuits are formed. In order to readily see if these simplex circuits are energized, normal or reverse, or are de-energized the leads of the secondary winding of the transformer 7² have been marked plus (+) and minus (-). From this it will be noted that under absolute stop-and-stay conditions of the block K, as shown, the first section of this block is energized by reverse or caution current, that is, minus to plus from left to right, the second section is energized by normal or clear current, that is, plus to minus and the third section of this block has its simplex circuit de-energized. Also, that when the lever 27 is depressed to its abnormal position the simplex circuit of the block K is the same as that of the block H or I of block signal territory; that is, is energized plus to minus under clear and is energized minus to plus under caution traffic conditions.

In the block H has been illustrated a typical railway vehicle such as an engine and tender unit by wheels and axles 17 and 18. In front of the first axle 17 of the railway vehicle and directly over each track rail are disposed car-carried elements comprising cores 19 having coils 20 contained thereon. The cores 19 preferably are constituted of laminated iron of high magnetic quality terminating in enlarged pole pieces. The coils 20 are connected in series so that voltages induced therein due to currents flowing in opposite directions in the two track rails are cumulative and have bridged across leads leading therefrom a condenser 21 of the proper capacity to resonate the coils 20 for the frequency of the railway signaling current, so that the potential across this condenser 21 is a maximum. These leads are connected to the input side of a track phase amplifying device AT which includes suitable amplifying tubes of the vacuum type, sources of energy, and tuning devices, and which has its output leads connected to the winding 22 of a main relay MR.

Similarly, cores 23 located in the rear of the last tender axle 18 have their coils 24 connected in series so that voltages induced therein due to currents flowing in the same

direction in the two track rails in multiple arc cumulative, the leads leading from these coils being similarly resonated by a condenser 25, and through a line phase amplifying device 5. All these coils are adapted to supply a current to the other phase winding 26 of the main relay MR.

The main relay MR is preferably one of the induction type which will assume its normal position when the railway vehicle moves in a clear block, in which trackway and line phase currents are flowing which have a normal phase relation preferably displaced substantially 90 electrical degrees; and obviously assumes the reversed position if the phase relation of one of these trackway circuits is reversed and assumes the de-energized position if one or both of these trackway circuits are cut off.

20 The present invention has been shown in a system which contemplates a gradual reduction in the permissive speed of the train as it passes through a caution block by the well known cam-and-governor arrangement, 25 in which a permissive speed cam is driven in accordance with the progress of the train through a caution block. Since this cam-and-governor speed control mechanism by itself does not constitute any part of the present 30 invention this mechanism will be briefly described, attention being directed to the application of W. K. Howe, Ser. No. 38,132 for a detailed description of such apparatus.

Referring to Fig. 2 this cam-and-governor mechanism diagrammatically illustrated is similar in many respects to that shown in the prior application to Howe Ser. 746,578 referred to. The shaft 30 is driven from the wheels of the vehicle in any suitable manner 35 and has a speed responsive device or centrifuge C of the well known centrifugal type mounted thereon. It is obvious from the drawings that the grooved collar 31 of the speed responsive device C moves downwardly as the speed of the train increases. Adjacent the shaft 30 and preferably at right angles thereto is a speed shaft 32 which has a bifurcated arm 33 pinned thereto of which suitable pins extending inwardly from the bifurcated end of this arm engage the groove in the collar 31, so that the shaft 32 is rocked to a position depending on the speed of the train. On this speed shaft 32 is secured a sector 34 which is adapted to close contacts 40 45 50 55 60 65 70 75 80 85 90 95 100 105 110 115 120 125 130 when the speed of the train is below 15 miles per hour, as indicated by the legend in Fig. 3.

On the shaft 30 is also suitably secured a worm 36 which is in continuous meshed engagement with a worm wheel 37 secured to the shaft 38, which shaft has a pinion 39 pinned thereto. The pinion 39 continuously meshes with the gear 40 pivotally supported on a journal 41. This journal 41 also pivotally supports the bifurcated end of an arm

42 which arm straddles the gear 40 and has a pinion 43 journaled therein which is in continued mesh relation with the gear 40. This arm 42 is urged upwardly by a spring 44 so as to tend to place the pinion 43 into meshed relation with the mutilated gear 45. Under normal clear traffic conditions, however, this arm 42 is held in its lower position, as shown, by a cam starter magnet HCS.

The mutilated gear 45 is fastened to the high cam shaft 46, this shaft being held in its normal position by a spring 49 engaging the free end of the arm 55 secured to this shaft 46. On the shaft 46 is contained a distance cam 47, which is adapted to operate contacts 48 at a point depending on the distance the train has traveled since the cam starter magnet HCS was de-energized as more clearly pointed out hereinafter.

To the speed shaft 32 is suitably secured an arm 51 to the free end of which is pivotally connected a floating lever 52, which lever has its free end bifurcated and provided with a roller 53 engaging the surface of a permissive speed cam 50. Obviously, since the arm 51 responds to the speed of the train and the cam 50 is shaped to move the roller 53, to set up permissive speed limits as the train proceeds with the cam starter magnet HCS de-energized, all that is necessary to open contacts when the actual speed of the train is too high as compared with the permissive speed is to cause these contacts to respond to the movement of an intermediate point on the floating lever 52. In the particular arrangement shown a sector 54 pivotally supported by a journal 54^a is provided, which sector has an eccentrically located pin 56 connected to an intermediate point of the floating lever 52 by a link 57, so that this sector is rocked toward the right as the speed increases and also as the train progresses, so that the speed must be reduced as the train progresses through the block. This sector 54 is biased in a counter clockwise direction by a spring 58 so as to hold the roller 53 against the cam 50. This sector 54 permits opening of the outwardly biased contacts 59 when the speed of the train is excessive. In a similar manner the low cam shaft 46^a for operating distance contacts only is provided, which shaft is turned in accordance with the progress of the train when the low cam starter magnet LCS is de-energized, and since various parts of these devices are the same like reference characters with distinctive exponents *a* have have been applied to such parts of the low cam shaft mechanism.

Referring now to Fig. 3 of the drawings, there has been shown in addition to the apparatus already referred to mechanism including an acknowledging relay Ack R, a penalty relay PR, and an electro-pneumatic valve EPV. The two relays just mentioned may be of any suitable type, but are preferably con-

structed so that their moving parts are not easily disturbed by the jars and vibration experienced on railway trains.

An automatic train control system of the speed control type obviously employs means for effecting an automatic brake application under predetermined conditions of speed depending on traffic conditions in advance of the train. Since the present invention does not relate to any specific brake applying mechanism, the device EPV has been illustrated as a device for operating a suitable pneumatically operated brake control device, which device is adapted to vent the brake pipe to a predetermined extent in a manner so that the engineer cannot recharge the same, or is adapted to control a brake valve actuator for operating the usual engineer's brake valve to the service position in a manner so that the engineer cannot prevent such automatic operation of the brake valve.

Fig. 3 shows the electrical connections between the various devices of the car apparatus; and in this circuit plan, various conventions have been adopted to simplify the illustration and facilitate explanation. The various contact fingers of the various relays are shown directly under the conventional illustration of the relay controlling them and are connected by dot and dash lines. Each distance shaft is similarly illustrated by a dot and dash line leading to the cam-starter magnet governing the same.

In order to facilitate the description of the various circuit changes that take place in the car-carried circuit arrangement shown in Fig. 3 it is considered advisable to trace the normally closed circuits first, after which the circuit changes may be considered as the train proceeds under various speed and traffic conditions.

The high cam starter magnet HCS is normally energized by the battery 60 through a circuit including the contact 61 of the main relay MR when this relay is in its normal clear traffic position, which circuit is readily traced in the drawings. Similarly the low cam starter magnet LCS is energized if the main relay MR is either in its normal or its reversed position through the following circuit:—beginning at the bus bar 62 connected to one side of the battery 60, wire 63, contact 64 of the main relay MR, wires 65 and 66 depending on whether the relay MR assumes its normal or reversed position, wire 67, winding of the low cam starter magnet LCS, wire 68, push button PB, wire 69 to the other bus 70 connected to the other terminal of the battery 60. With the cam starter magnets HCS and LCS energized the distance shafts 46 and 46^a assume the normal position as shown in Fig. 2.

Under clear traffic conditions as illustrated the penalty relay PR is energized by the following stick circuit:—beginning at the bus

62, wire 71, contacts 48^a operated by the distance cam 47^a, wires 108, 72 and 73, distance contact 48 operated by the distance cam 47, wires 74, 75, 76 and 77, front contact 78 of the penalty relay PR, wires 79 and 80, winding of the penalty relay PR, wire 81 to the other bus 70. It should be noted that the penalty relay PR is also energized under clear traffic conditions by a circuit including contact 82 of the main relay MR which is readily traced in the drawings and includes the greater part of the circuit just traced. The purpose for which this circuit has been provided is more readily pointed out hereinafter. The device EPV is normally energized through the following circuit:—Starting at the bus 62, wire 83, cam and governor contacts 59, wires 84, and 85, distance contacts 86 operated by the distance cam 87, wires 88 and 89, front contact 90 of the penalty relay PR, wire 91, winding of the EPV, wire 92 to the bus 70.

Operation in block signal territory.—By looking at the circuit for the device EPV just traced it readily appears that this device is de-energized if either the penalty relay PR is de-energized, the speed of the train is in excess of the speed set up by the permissive speed cam 50 as manifested by the opening of contacts 59, or if the contacts 86 of the cam 87 are open while the contacts 35 of the speed cam 34 are open due to the train speed being above 15 miles per hour.

In order to facilitate explanation, let us assume that the train in question equipped with the car apparatus shown in Fig. 3 in its normal condition is moving from left to right in the block H when the block I in advance thereof is a caution block, that is, with the block I unoccupied and the block J occupied by another train. So long as the train moves in a clear block only a certain maximum speed restriction is enforced which for the particular cam shown is 60 miles per hour as indicated by the curve 93 in Fig. 1 of the drawings. If the train exceeds this speed at any time an automatic brake application occurs, after which brakes may again be released by the engineer as soon as the speed is no longer excessive. As the train in question enters the block I the alternating current impressed on the winding 26 of the main relay MR is reversed, because the line phase circuit in the block I has its polarity reversed by reason of dropping of contacts 10¹ and 15¹ of the track relay 3¹. This causes the main relay MR to swing its contacts 61, 64 and 82 to the left, thereby de-energizing the high cam starter magnet HCS and opening one of the circuits heretofore mentioned for energizing the penalty relay PR, namely, the circuit including the contact 82 of the relay MR, this relay PR however still being maintained energized through the other circuit traced. With the high cam starter magnet HCS de-energized the high cam shaft 46 is gradually

rotated, thereby decreasing the permissive speed of the train gradually as indicated by the curve 93 in Fig. 1 of the drawings. After a short distance of movement in the caution 5 block the distance cam 94 closes contacts 95, as indicated by the solid portion of the line 95 in Fig. 1 of the drawings thereby closing a circuit which sounds the acknowledging signal *Ack S* by the energization of the following circuit:—beginning at the bus 62, wires 96 and 97, acknowledging signal *Ack S*, wire 98, back contact 99 of the acknowledging relay *Ack R*, wires 100 and 101, contacts 95 operated by the distance cam 94, wires 102 10 and 103 to the other bus 70. The sounding of this acknowledging signal informs the engineer that he must perform an acknowledging act to show his vigilance and in turn avoid an automatic brake application. If the 15 engineer now presses the acknowledging push button *PB* a pick-up circuit for the acknowledging relay *Ack R* is completed, which may be traced as follows:—beginning at the bus 62, wires 96 and 104, winding of the acknowledging relay *Ack R*, wires 105 and 106, push button *PB*, wire 69 to the other bus 70. It 20 should be noted that with this acknowledging relay *Ack R* energized, the circuit for energizing the acknowledging signal *Ack S* 25 is broken. With this relay *Ack R* once picked up a stick circuit for this relay is completed as follows:—beginning at the bus 62, wires 96 and 104, winding of the acknowledging relay *Ack R*, wires 105 and 107, front contact 30 99 of the relay *Ack*, wires 100, and 101, distance contact 95, wires 102 and 103 to the other bus 70.

After the train has proceeded a little further the distance contacts 48 operated by the 40 cam 47 are opened for a short distance of travel as indicated by the interrupted portion of the line 48 in Fig. 1 of the drawings. The opening of contacts 48 breaks the stick circuit for the penalty relay *PR* heretofore traced which includes these contacts 48, but since the engineer has manifested his vigilance by depressing the push button *PB* and sticking up the acknowledging relay *Ack R*, an auxiliary stick circuit for the penalty 45 relay *PR* is completed, which may be traced as follows:—beginning at the bus 62, wire 71, contacts 48^a operated by the distance cam 47^a, wires 108 and 109, front contact 110 of the acknowledging relay *Ack R*, wires 111 and 50 112 and 77, front contact 78 of the penalty relay *PR*, wires 79 and 80, winding of this relay *PR*, wire 81 to the other bus 70.

After another short distance of travel of the train the contacts 48 are closed and the 55 contacts 95 are opened. The opening of contacts 95 causes dropping of the acknowledging relay *Ack R* so as to again place it in its normal condition. As the train proceeds through the block I the engineer is obviously 60 required to reduced his speed as indicated

by the curve 93 to avoid an automatic brake application by opening of the permissive speed contact 59.

Near the end of the block I the distance shaft 46 will have reached its ultimate position wherein the pinion 43 engages the mutilated portion of the mutilated gear 45, after which the permissive speed is constant as indicated by the horizontal line 113 (see Fig. 1). Also just before the high cam shaft 46 reaches its ultimate position the contacts 114 operated by the distance cam 115 are closed as indicated by the solid portion of the line 114 in Fig. 1 of the drawings. The closing of these contacts does not complete a circuit but permits another auxiliary acknowledging circuit to be completed as more clearly pointed out hereinafter.

As the train proceeds into the block J, which is assumed to be occupied by said another train, no track phase current can be detected in the elements located in front of the first axle of the train because this current is shunted away by said another train in advance. This causes the main relay *MR* 85 to assume its de-energized position so as to de-energize the low cam starter magnet *LCS*. With this cam starter magnet *LCS* de-energized the low cam is gradually rotated in accordance with the progress of the train and 90 after a short distance of movement of the train the contacts 95^a are closed, as indicated by the line 95^a in Fig. 1, thereby again sounding the acknowledging signal *Ack S* through a circuit which is obvious from the drawings. 100 The sounding of the acknowledging signal *Ack S* advises the engineer that he must depress the push button *PB* to manifest his vigilance and that he is now entering an occupied block. Depression of the push button *PB* again picks up the acknowledging relay *Ack R*, which relay after once picked up is stuck up through the same stick circuit heretofore traced except that the present circuit 105 includes contacts 95^a and not 95.

Upon a slight further movement of the train in the occupied block the contacts 48^a are opened as indicated by the horizontal line 48^a (see Fig. 1) which interrupts the stick circuit for the penalty relay *PR* heretofore traced. The penalty relay is, however, not de-energized because it is now energized through the following circuit:—beginning at the bus 62, wire 118, contacts 114 operated by the distance cam 115, wire 119, front contact 110 of the penalty relay *PR*, wires 121, 112 and 77, front contact 78 of the penalty relay *PR*, wires 79 and 80, winding of the penalty relay *PR*, wire 81 to the bus 70. In other words, the engineer has avoided de-energization of the penalty relay *PR* by depressing the push button *PB* in response to the acknowledging signal *Ack S*. At about the same time that contacts 48^a open the contact 115 120 is permitted by the cam shaft 46^a to also 125 130

open, as indicated by the line 86 in Fig. 1 of the drawings. With the contacts 86 open the device EPV relies for its energizing current upon the continuity of the circuit through 5 speed contacts 35 which are only closed if the speed of the train is less than say, 15 miles per hour.

At first hand it would appear that the contacts 35 and 86 are unnecessary, because the 10 contacts 59 are already open if the speed of the train is over 15 miles per hour under the assumed conditions. There are however conditions where this is not true and these contacts 35 and 86 are essential. For instance, 15 assume the train to be moving at a very slow speed near the end of a block and a switch is opened in the block next in advance; under this condition the high cam would not yet have been run down when the train reaches 20 the end of the block and under this condition the contacts 35 would set up the restricted speed limit.

It may be stated at this time that contact 82 of the main relay MR has principally been 25 provided to prevent the requirement of acknowledgment when either the high or the low cam shaft are restored to their normal position, during which time the contacts 48 or 48^a, as the case may be, are open; and it will 30 be noted that these contacts are shunted by the contact 82 during the restoration of these cam shafts, so the penalty relay is not dropped. For instance, if traffic conditions change from danger to caution (both the high 35 cam 47 and the low cam 47^a in the run-down position) movement of the contact 82 from its neutral to its left-hand position closes the following circuit for the penalty relay PR:— beginning at the battery 60, bus wire 62, contact 40 82 of the main relay MR in its left-hand position, wire 73, contacts 48 of the high distant cam 47, wires 74, 75, 76, and 77, stick contact 78, wires 79 and 80, winding of the penalty relay PR, wires 81 and 70 back to battery 60. Momentary opening of contacts 48^a 45 due to reenergization of the cam starter magnets LCS will not effect deenergization of the relay PR by reason of the presence of the auxiliary circuit just traced. Also, change in 50 traffic conditions from danger or caution to clear will not permit deenergization of the penalty relay PR even though contacts 48 are momentarily opened because the following auxiliary circuit is first closed:—beginning at 55 the battery 60, wire 62, contact 82 of relay MR assuming the right-hand position, wires 76 and 77, stick contact 78 of the penalty relay PR, wires 79 and 80, winding of the penalty relay PR, wires 81 and 70 back to battery 60. When either of these cams is 60 restored to its normal position the acknowledging signal *Ack S* is momentarily sounded; since this momentary sounding of the signal can readily be distinguished from the sounding 65 when acknowledgment is required it may

be used to inform the engineer that a favorable change in traffic conditions has taken place. The difference in the time during which this signal sounds when the cams are run down and restored respectively, is due to 70 the fact that these cams are driven slowly from their normal position and are almost instantly restored by the spring 47 or 47^a to the normal position. It should be noted that the push button PB is protected against misuse, that is, it cannot be permanently tied down, for by so doing the cam starter magnet LCS is de-energized and the minimum speed limit of 15 miles per hour is immediately thereafter set up and continues so long as this 80 push button is tied down.

From the above it appears that the engineer is required to make an acknowledging act when a change of traffic conditions from clear to caution takes place, and also when a 85 change of traffic conditions from caution to danger takes place.

Operation at the approach to a stop-and-stay signal.—Let us now consider the movement of a train during its approach to a 90 stop-and-stay signal. Let us assume that a train equipped with the car-carried apparatus shown in Figure 3 enters the block K when a conflicting route is set up that is, the lever 27 is in normal position and the tower 95 man cannot change this lever from its normal position. As the train enters the block K, consequently the engineer is required to acknowledge this change in traffic conditions and thereafter is required to restrict his speed 100 in accordance with the permissive speed limit set up by the cam 50, as shown by the curve 93 in Fig. 1, so that the train has practically reached its minimum speed of 15 miles per hour when it reaches the balancing resistance 28. As heretofore mentioned, the section between balancing resistances 28 and 29 is provided with simplex current of normal 105 polarity so that the relay MR is again energized to its normal position for a short distance *k* of movement as indicated in the block K. This restores the high cam to its normal position, and as the train proceeds in the face of the absolute stop-and-stay signal ZA at danger, and passes beyond the balancing resistance 29, a sudden change from clear to 110 danger takes place because there is not simplex circuit current present between the balancing resistances 29 and 12^a, so that, the relay MR changes from its normal to its de-energized position abruptly. This change of the main relay MR causes both the high cam shaft 46 and the low cam shaft 46^a to be started at the same time, and after a short distance of movement the acknowledging signal *Ack S* is sounded for reasons heretofore given. Even if the engineer now presses the push button PB for reasons heretofore given, this will avail him nothing, because 115 the contacts 114 have not yet closed, so that, 120 125 130

the circuit for maintaining the penalty relay PR up including this contact 114 and the contact 120 of the acknowledging relay Ack R, is not complete at the time contacts 48 and 48^a are open; and this relay PR is de-energized and an automatic brake application occurs. It is assumed that this brake application is sufficient warning to the engineer that he will not continue movement of his train after 10 it has been brought to a stop.

The distance contact cams 47 and 47^a are preferably so designed that the contacts 48 and 48^a will have been reclosed before the train has been brought to a stop by the automatic brake application just mentioned, and as soon as the train has been brought to a stop, a pick-up circuit for the penalty relay PR is completed which may be traced as follows:—beginning at the positive bus 62, wire 71, contacts 48 and 48^a, wire 74, contacts 122 which are only closed when the train is substantially at a stop, wires 123 and 80, winding of the penalty relay PR, wire 81 to the negative bus 70. The completion of this circuit obviously causes the penalty relay to assume its attracted position after which the stick circuit is completed and the penalty relay PR is again stuck up, so that the engineer may proceed if he desires to do so. 30 The engineer will, of course, not proceed until the stop-and-stay signal ZA, assumes its clear position, which it will as soon as the tower man changes the lever 27 controlling this signal to its abnormal proceed position, 35 it being assumed, of course, that traffic conditions ahead are clear.

In order to assure that a change from clear to danger takes place at the approach of the train to an absolute stop-and-stay signal, the trackway circuits necessary to energize 40 the relay MR to its clear position may be checked in any one of the well known ways, for instance, the wire leading to the mid-point of balancing resistance 29 may have a 45 check relay therein which must be energized before a conflicting route can be set up, so that the possibility of a failure of proper operation of the absolute stop mechanism is very remote.

50 A train control system embodying the present invention has certain advantages over other train control systems of the continuous inductive type having absolute stop features incorporated therein heretofore proposed, in 55 that, a failure of trackway energy by reason of transmission line trouble, or the like, merely effects a brake application regardless of speed after which the train may again proceed at the discretion of the engineer.

60 Although in the simplified train control system shown, no specific means has been shown for cutting out the automatic apparatus when the train enters the territory not equipped for train control, it is to be understood that suitable apparatus for this pur-

pose is in most instances necessary. If such means is to be employed in a system embodying the present invention it is proposed to employ the arrangement for picking up a non-control territory stick relay disclosed in 70 the application of C. S. Bushnell, Ser. #723,048 filed June 28, 1924, to which reference may be made for this purpose.

Having thus shown and described one 75 rather specific embodiment of the present invention and having shown it applied to a simple alternating current block signal system, it is desired to be understood that the specific apparatus illustrated has been selected for the purpose of disclosing means 80 for carrying out the invention rather than for the purpose of illustrating the particular apparatus preferably employed in practice or the scope of the invention, and that various changes, modifications and additions 85 may be made to adapt the invention to various other types of railway signaling systems or to systems in which no wayside signals are used and suitable cab signals controlled by the main relay MR are employed, 90 all without departing from the scope of the invention or the idea of means underlying the same.

What is claimed as new and desired to be 95 secured by Letters Patent is:—

1. Car-carried apparatus for automatic 100 train control systems comprising, two delayed action devices one of which is initiated upon a change of traffic conditions from clear to caution and the other of which is initiated upon a change from caution to danger, means 105 for restricting the speed of the train differently when one or the other of these devices is initiated, and means for effecting an automatic brake application regardless of the speed of the train if both of said delayed action devices are initiated simultaneously.

2. Car-carried apparatus for automatic 110 train control systems comprising, means for restricting the speed of the train to a given limit upon a change of traffic conditions from clear to caution, means for further restricting the speed of the train to a lower limit in response to a change in traffic conditions from caution to danger, and means for stopping 115 the train regardless of speed only upon an abrupt change of traffic conditions from clear to danger.

3. Car-carried apparatus for automatic 120 train control systems comprising, brake applying means for effecting a brake application if a change of traffic conditions from clear to caution, from caution to danger or from clear to danger takes place, manually operable acknowledging means which if actuated when a change of traffic conditions from clear to caution or from caution to danger takes place prevents a brake application by said brake applying means but which is incapable of preventing a brake appli- 125 130

cation if operated when a change of traffic conditions from clear to danger takes place.

4. Car-carried apparatus for automatic train control systems comprising, means for giving a signal and for effecting a brake application if a change of traffic conditions from clear to caution, from caution to danger or from clear to danger takes place, manually operable acknowledging means which if actuated immediately after said signal is given prevents a brake application by said first mentioned means upon a change from clear to caution or caution to danger but which is incapable of preventing a brake application if operated when a signal is given in response to a change of traffic conditions from clear to danger.

5. In an automatic train control system; the combination of car-carried apparatus comprising, an electro-responsive device adapted to assume three different positions in response to clear, caution and danger traffic conditions ahead respectively, means for restricting the speed of the train upon a change in traffic conditions from clear to caution, another means for restricting the speed of the train upon a change in traffic conditions from caution to danger, and means for effecting a brake application regardless of train speed when a change in traffic conditions from clear to danger takes place; and of trackway apparatus at the approach to a stop-and-stay signal for causing said relay to change from clear to danger as the train approaches said stop-and-stay signal thereby stopping the train upon its approach to such signal regardless of the speed of the train at the time.

6. In an automatic train control system for railroads; the combination of car-carried apparatus including a slow acting device changing in accordance with the progress of the vehicle when active and initiated upon a change in traffic conditions from clear to caution, another similar slow acting device initiated upon a change in traffic conditions ahead from caution to danger, a manually operable device, means for effecting an automatic brake application when either of said devices are initiated unless said manually operable device is operated and effective to automatically apply the brakes regardless of the operation of said manually operable device when both of said slow acting devices are initiated simultaneously; and of trackway means at the approach to a stop-and-stay signal for manifesting on the car traffic conditions corresponding to a change from clear to danger as the car approaches said signal, thereby effecting a brake application regardless of whether or not the engineer operates said manually operable device.

7. In an automatic train control system for railroads; the combination of car-carried ap-

paratus including a slow acting device changing in accordance with the progress of the vehicle and initiated upon a change in traffic conditions from clear to caution, another similar slow acting device initiated upon a change in traffic conditions ahead from caution to danger, a manually operable device, means for effecting an automatic brake application when the train has traveled a predetermined distance after either of said devices are initiated unless said manually operable device is operated and effective to automatically apply the brakes regardless of the operation of said manually operable device when the train has traveled a predetermined distance after both of said slow acting devices are initiated simultaneously; and of trackway means located at the approach of a stop-and-stay signal for manifesting on the car traffic conditions corresponding to a change from clear to danger when the car approaches said signals, whereby an automatic brake application is effected regardless of whether or not the engineer operates said manually operable device after the train has traveled said predetermined distance with both of said slow acting devices initiated.

8. In an automatic train control system, traffic controlled trackway means for transmitting influences corresponding to traffic conditions to a moving vehicle, such influences changing from clear to caution and from caution to danger in response to increasingly unfavorable traffic conditions ahead, and changing from clear to danger at certain points along the trackway where a stop is required, car-carried apparatus comprising means for restricting the speed of the train to a given limit upon a change of said influences from clear to caution, means for further restricting the speed of the train to a lower limit in response to a change of said influences from caution to danger, and means for stopping the train regardless of speed only upon a change of influences directly from clear to danger.

9. In an automatic train control system, traffic controlled trackway means for producing on a moving vehicle three different signal impulses in a given sequence under certain trackway conditions, and for producing a different sequence of impulses under other trackway conditions, car-carried means responsive to said impulses for producing a given degree of control in response to said given sequence of impulses and responsive irrespective of manual control for producing a different degree of control in response to said different sequence of impulses.

10. In an automatic train control system, car-carried apparatus comprising means for restricting the speed of the vehicle upon the reception of three distinctive signal impulses in a given sequence, and means for stopping

the train only upon the reception of two of said signal impulses in a different sequence.

11. In an automatic train control system, car-carried apparatus including means for giving a permissive stop control of the car upon reception of at least three distinctive signal impulses in a given sequence, and an absolute-stop control of the car upon reception of impulses in a different sequence.

10 12. In an automatic train control system, car-carried apparatus including means for giving a permissive stop control of the car upon each change of at least three received distinctive signal impulses in a consecutive 15 order of less to more restrictive character.

and an absolute stop control of the car upon change of impulses in a non-consecutive order.

13. In an automatic train control system, traffic controlled trackway means for producing on a moving vehicle at least three different signal impulses in a given sequence, traffic controlled trackway means for producing a different sequence of impulses, and car-carried means responsive to said impulses for giving a permissive stop control in response 20 to said given sequence of impulses and for giving an absolute stop control in response to said different sequence of impulses.

In testimony whereof I affix my signature.
FRANK L. DODGSON.
